US0D1013775S

(12) **United States Design Patent** (10) **Patent No.:** **US D1,013,775 S**
(45) **Date of Patent:** **** Feb. 6, 2024**

(54) **LABEL SHEET**

(71) Applicant: **CCL Label, Inc.**, Framingham, MA (US)

(72) Inventors: **Jay Sato**, Mission Viejo, CA (US); **Laura Cruz**, Placentia, CA (US); **Jenifer Do**, Fullerton, CA (US)

(73) Assignee: **CCL LABEL, INC.**, Framingham, MA (US)

(**) Term: **15 Years**

(21) Appl. No.: **29/818,127**

(22) Filed: **Dec. 7, 2021**

Related U.S. Application Data

(62) Division of application No. 29/729,233, filed on Mar. 25, 2020, now Pat. No. Des. 940,235, which is a division of application No. 29/679,265, filed on Feb. 4, 2019, now Pat. No. Des. 882,681, which is a division of application No. 29/638,602, filed on Feb. 28, 2018, now Pat. No. Des. 839,956, which is a division of application No. 29/553,826, filed on Feb. 4, 2016, now Pat. No. Des. 813,942.

(57) **CLAIM**

The ornamental design for a label sheet, as shown and described.

DESCRIPTION

FIG. 1 is a front view of a first embodiment of a label sheet showing our new design;

FIG. 2 is a left side view thereof;

FIG. 3 is a right side view thereof;

FIG. 4 is a top view thereof;

FIG. 5 is a bottom view thereof;

FIG. 6 is a back view thereof;

FIG. 7 is a front view of a second embodiment of a label sheet showing our new design;

FIG. 8 is a left side view thereof;

FIG. 9 is a right side view thereof;

FIG. 10 is a top view thereof;

FIG. 11 is a bottom view thereof; and,

FIG. 12 is a back view thereof.

The broken lines in the figures are included for the purpose of illustrating portions of the label sheet and form no part of the claimed design.

1 Claim, 6 Drawing Sheets
